SUPPORTING RACK FOR A VACUUM COFFEE MAKER UPPER BOWL

William E. Taylor, Long Beach, Calif.

Application June 25, 1951, Serial No. 15,648

Term of patent 14 years

(Cl. D44—26)

To all whom it may concern:

Be it known that I, William E. Taylor, a citizen of the United States, residing at Long Beach, State of California, have invented a new, original, and ornamental Design for a Supporting Rack for a Vacuum Coffee Maker Upper Bowl, of which the following is a specification, reference being had to the accompanying drawing, forming a part hereof.

Figure 1 is a perspective view of a supporting rack for a vacuum coffee maker upper bowl showing my new design;

Figure 2 is a perspective view of the device oppositely disposed from that shown in Figure 1; and,

Figure 3 is a top plan view thereof.

I claim:

The ornamental design for a supporting rack for a vacuum coffee maker upper bowl, as shown.

WILLIAM E. TAYLOR.
